DOUBLE DUTY SNOW PLOW

Archie O. Williamson, Minneapolis, Minn.

Application April 25, 1938, Serial No. 204,113

14 Claims. (Cl. 37—43)

This invention relates to a snow plow and particularly to a snow plow constructed and arranged to act as a plain push plow when the snow is of small depth and also to act as a rotary plow when the snow is of great depth.

In the ordinary practice of clearing roads if the snow is not of great depth a push plow is used. Such a plow has a moldboard with laterally and rearwardly extending curved surfaces designed to move the snow to the sides of the road and discharge the same from the road. Such plows can be moved along the road at comparatively high speeds when the fall of snow is not heavy. When the fall of snow is heavy and 10 the snow has accumulated in considerable depth upon the road and where drifts of considerable depths have formed it is necessary to have a power plow or a rotary plow to move the snow. Such power or rotary plows have heretofore been 20 entirely separate units from the push plows and only brought into service when considerable depths of snow were encountered.

As above stated, it is an object of this invention to provide a plow which might be called a 25 double duty plow and one constructed and arranged to act both as a push plow and as a power rotary plow.

It is another object of the invention to provide 30 a snow plow having a moldboard with laterally and rearwardly extending curved surfaces for moving and discharging snow if the snow is not of great depth, said moldboard having at a considerable height and adjacent the top thereof rotary conveyors which will engage and remove 35 the snow if the snow is of great depth.

It is a further object of the invention to provide 40 a chamber to which the snow is moved by said conveyors, means for discharging snow from said chamber, a deflector for directing the snow to one side of the road or the other and means for driving said means in opposite directions respectively in accordance with the position of said deflector.

It is still another object of the invention to 45 provide a double duty plow of simple and compact construction adapted to be propelled by a vehicle together with means for driving the operating parts from a motor on said propelling vehicle.

These and other objects and advantages of the 50 invention will be fully set forth in the following description made in connection with the accompanying drawings in which like reference characters refer to similar parts throughout the several views and in which:

Fig. 1 is a view for the most part in front eleva-

tion of the plow, a portion thereof being shown in vertical section taken substantially on line 1—1 of Fig. 3 as indicated by the arrow, a portion of said plow also being broken away:

Fig. 2 is for the most part a top plan view of 5 the plow, some parts being shown in horizontal section taken substantially on line 2—2 of Fig. 3 as indicated by the arrow;

Fig. 3 is a central vertical section through the plow;

Fig. 4 is a partial vertical section taken substantially on line 4—4 of Fig. 2;

Fig. 5 is a vertical section taken on line 5—5 of Fig. 3 as indicated by the arrow; and

Fig. 6 is a vertical section taken on line 6—6 of Fig. 3.

Referring to the drawings a snow plow is shown comprising a moldboard designated generally as 10 and having similar side portions 10a and 10b which extend laterally and rearwardly from a 20 central vertically extending line or prow 10c. The surface of the portions 10a and 10b is somewhat curved as indicated by the outer end lines in Fig. 2 and the surfaces of portions 10a and 10b are designed to move the snow laterally as the 25 plow is pushed forward into the snow, the snow thus moving outwardly and rearwardly along said surfaces until it is finally discharged at the outer ends of said portions and at one side or both sides of the road. The surfaces 10a and 10b 30 extend upwardly for a considerable distance which in practice would be over three feet. At or adjacent the tops of the moldboard portions 10a and 10b each portion is provided with a rearwardly extending substantially semi-cylindrical portion 10d forming at its forward side, a substantially semi-cylindrical recess or trough which 35 extends from adjacent the center of the moldboard to the outer end thereof. A casing 10e is formed at the central top portion of the moldboard, the same having bearings 10f at either side thereof and bearings 11 are provided closely adjacent the outer ends of the trough-shaped portions 10d. Shafts 12 are journalled at their 40 inner ends respectively in bearings 10f and at 45 their outer ends in the bearings 11. Said shafts have thereon helical blades 12a forming screw conveyors. A casing 13 is provided in the rear of moldboard 10 at the center thereof and said casing has a chamber 13a therein with which 50 the troughs formed by portions 10d communicate. The conveyors formed by shafts 12 and the blades 12a are rotated so as to move snow engaged thereby inwardly toward the center of the plow and this snow is discharged into cham-

ber 13a. Each shaft 12 has secured to its inner end a bevelled gear 14. It will be noted that bearings are provided for the shaft at either side of gear 14 and while these bearings might be of various forms, in the embodiment of the invention illustrated they are shown as ball bearings. Each gear 14 meshes with another bevelled gear 15 carried on a shaft 16 having bearings in portions of casing 10e and to the central part of which is secured a spur pinion 17. Pinion 17 meshes with a large spur gear 18 forming an idler and carried on a short shaft 19 having bearings at either side of gear 18 in the wall of casing 10e. It will be seen in Fig. 3 that casing 10e has a rear wall 10g. A bearing member 20 is suitably secured in an opening in rear wall 10g shown as having longitudinally spaced bearings for a shaft 21. Shaft 21 has secured to its forward end a bevelled pinion 22 which meshes with a bevelled gear 23 having secured thereto or integral therewith as shown in Fig. 6 a spur pinion 24 which meshes with and drives the spur gear 18. Gears 23 and 24 have stub shafts or trunnions 25 journaled respectively in bearings 26 illustrated as ball bearings and carried in the sides of casing 10e. Shaft 21 at its other end is connected by universal joint 27 to a shaft 28 which has a splined portion 28a embraced by a short sleeve 29 in turn connected to a universal joint 30. Universal joint 30 will be connected to a shaft extending to or connected to a motor on the vehicle which propels the plow. The parts of the plow will thus be driven by said motor and by the shaft connected to joint 30. Another small gear or pinion 31 is disposed above and meshes with spur gear 18. This pinion has a shaft 32 extending at either side thereof and oppositely disposed bevelled gears 33 and 34 are carried on this shaft at either side of pinion 31. Gears 33 and 34 have hub portions carried in bearings disposed in plates or partitions 35 carried in a casing 10h which has end sections secured respectively at opposite sides of casing 10e at the upper portion thereof as clearly shown in Fig. 1. Shaft 32 has splined portions at either end on which are slid able clutch members 36 and 37 respectively. Members 36 and 37 have clutch teeth at their inner ends adapted to engage with clutch teeth on the outer ends of the hubs of gears 33 and 34 respectively. Clutch forks 38 and 39 engage in grooves formed in members 36 and 37 respectively and are secured to a rod 40 slid able in bearings in plates 35. Rod 40 has a pin 40a projecting horizontally therefrom and engaged by a fork at the lower end of a clutch lever 41 pivoted at 42 in the top of casing 10h, said lever projecting through and above said top and shown as having a ball at its upper end. A bevelled pinion 43 meshes with gears 33 and 34 and is secured to a shaft 44 extending horizontally and rearwardly from said pinion 43. Shaft 44 is journaled in spaced bearings illustrated as ball bearings and disposed in a bearing sleeve 45 secured in rear wall 10g. Shaft 44 is connected by a coupling 46 to a shaft 47 to which is secured a propeller 48 disposed in a substantially cylindrical rear portion of casing 13. Casing 13 has a discharge opening 13c above propeller 48 and has upwardly extending side portions 13b of substantially triangular form adjacent the top or apex of which is pivoted a deflector 50 having pivot members 51 supported in portions 13b. Shaft 47 is carried in bearings 51 disposed in a bearing casing 52 secured to the rear side of the casing 13. The bottom portion of casing 10e is

shown at 10i and bulkhead plates 53 are disposed vertically in the rear of the moldboard beneath bottom plate 10i and at some distance at either side of the central portion of the plow, said plates extending to the rear side of said moldboard. A vertical plate 60 extends transversely of the plow at the rear edges of plates 53. An angle member 54 extends across the bottom of the plow in the rear of the moldboard and has apertured lugs 55 adjacent its outer ends to which push bars will be connected. Shoes 56 are also disposed at the bottom of the moldboard at either side thereof and secured to suitable vertical plates 57 having their rear portions turned outwardly as shown at 57a. A front central shoe 58 is also disposed beneath the forward portion of the moldboard and secured to angle members 54. Apertured lugs 59 are also disposed in the rear of the moldboard at points disposed some distance above the lugs 55, the same being secured to plates 53 and these will also be connected to a push bar for propelling the plow. Plates 62 of general triangular form are provided at each side of the moldboard adjacent the rear thereof and are pivoted to pivots 61 secured in plates 57 at 25 the lower front corners thereof. Said plates may be disposed with their lower surfaces horizontal as shown in the full line position in Fig. 3 or they may be raised to different positions by having bolts pass therethrough and through anyone of 30 the holes 57a formed in plates 57. A shoe 63 having an upwardly curved top and curved forward and lower end is secured at the bottom of the plow 10c.

In operation, the plow will be pushed along the road to be cleared by a propelling vehicle such as a truck or tractor and will be propelled by push bars connected to the lugs 55 and 59. The plow will ride on the shoes 56 and 58. If the snow to be cleared is not deep and not over 40 a depth of approximately two or three feet the plow will be used as a push plow. It will merely be pushed along the road with shaft 28 not driven. The snow will be engaged by the moldboard and moved by the side portions thereof to 45 the side of the road and discharged at the sides of the road. The plow is comparatively light and it can be moved and used as a push plow at comparatively high speed. Should some deep snow or drifts be encountered which cannot be cleared 50 by a push plow shaft 28 will be driven through the sleeve 29 from a motor on the propelling vehicle and spur gear 18 will be driven through the gears 22, 23 and 24. This will drive pinion 17 and shafts 12 will be driven through the gears 55 15 and 14. The conveyors formed by shafts 12 and the blades 12a will thus be rotated and these will engage the snow, cut into the same and move the snow inwardly toward the center of the plow. The snow will be discharged into the 60 chamber 13a. As the snow accumulates in said chamber it will be engaged by the propeller 48 and discharged at high velocity through opening 13c and will be deflected by deflector 50 to one side of the road. The snow will be moved with 65 sufficient velocity to be well off the road. Propeller 48 will be driven in opposite directions depending on the position of the deflector 50. With the deflector shown in the full line position in Fig. 5 the propeller will move in a clockwise direction. If the deflector is moved to the dotted line position in Fig. 5 the propeller will be driven in a counterclockwise direction. The direction of drive of propeller 48 will be determined by which one of the gears 33 or 34 is con- 70 75

5 nected to the shaft by engaging the clutch members 36 and 37. This can be easily done by manipulating lever 41. It will be noted that the snow is discharged to either side of the road in 5 exactly the same manner and with the same force by having the deflector 50 in one position or the other.

10 It will be understood that as the plow is pushed forwardly the snow is encountered and divided 10 by the prow portion or plate 10c and the lower shoe 63. The snow then moves rearwardly on the portions 10a and 10b. The plates 62 are provided so that the snow will be cut at the rear and outer sides of the moldboard. As de- 15 scribed these plates may be raised to different positions. By cutting the snow with these plates a clean swath is insured. Without said plates the outer end of the moldboard would merely 20 scrape along the snow and the snow would be broken and left in irregular formation. By the 20 use of the plates a clean cut and a substantially vertical or slightly inclined bank is insured.

25 From the above description it will be seen that I have provided a quite simple and very effective 25 double duty plow of compact structure. As above explained the plow is adapted for use both as a push plow and as a power rotary plow. The construction will insure that the plow will 30 withstand the heavy duty required and will be 30 strong and durable. It is apparent that the device will have a high degree of utility for the purpose intended.

35 It will, of course, be understood that various 35 changes may be made in the form, details, ar- arrangement and proportions of the parts, without departing from the scope of applicant's inven- 40 tion, which generally stated, consists in a device capable of carrying out the objects above set forth, in the parts and combinations or parts 45 disclosed and defined in the appended claims.

45 What is claimed is:

45 1. A snow plow having a mold board extending outwardly and rearwardly from a central ver- 50 tically extending line, said moldboard extending upwardly for a considerable distance whereby snow of small depth may be discharged laterally by 55 said moldboard and rotary conveyors disposed adjacent the top of said moldboard and extending longitudinally thereof in opposite directions 60 respectively for engaging and moving snow along 65 said moldboard if it is of great depth and means for driving said conveyors.

65 2. A snow plow having a moldboard extending outwardly and rearwardly from a central vertical- 70 ly extending line, said moldboard extending upwardly for a considerable distance whereby snow of small depth may be discharged laterally by 75 said moldboard, said moldboard having rearwardly extending substantially semi-cylindrical re- 80 cesses adjacent its top and rotary conveyors dis- 85 posed in said recesses and projecting somewhat therefrom for engaging and moving snow if it is of great depth and means for driving said convey- 90 ors.

95 3. A snow plow having a moldboard with sur- 100 faces extending outwardly and rearwardly, said moldboard extending upwardly for a consider- 105 able distance whereby snow of small depth may be discharged laterally by said moldboard and ro- 110 tary conveyors having helical blades thereon dis- 115 posed adjacent the top of said moldboard and ex- 120 tends outwardly and rearwardly from the central portion thereof for engaging and moving snow if it is of great depth and means for driving 125 said conveyors.

4. A snow plow having a moldboard with sur- 5 faces extending outwardly and rearwardly from the front thereof, said moldboard extending upwardly for a considerable distance whereby snow of small depth may be discharged laterally by 5 said moldboard, said moldboard having recesses at its top extending rearwardly therein, bearings adjacent the center of said moldboard and at the outer ends thereof, shafts journaled in said bearings and extending from adjacent the center of said moldboard laterally and rearwardly, and helical blades carried by said shaft disposed partially in said recesses and means for driving 10 said conveyors for engaging and moving snow toward the center of said moldboard if said snow is of great depth.

5. A snow plow having a moldboard extending outwardly and rearwardly through the center thereof, said moldboard extending upwardly for a considerable distance whereby snow of small 20 depth may be discharged laterally by said mold- 20 board, a casing having a chamber therein at the central top portion of said moldboard and at the rear thereof, conveyors extending along the top of said moldboard at either side thereof for 25 engaging and moving snow if it is of great depth, means for driving said conveyors for moving said snow inwardly and discharging the same in 30 said chamber.

6. The structure set forth in claim 5, said 30 chamber having a discharge opening at its top, a swinging deflector adapted to be disposed in opposite positions and means in said chamber for propelling snow therefrom through said open- 35

35 7. A snow plow having a moldboard extending outwardly and rearwardly from a central ver- 40 tically extending line, said moldboard extending upwardly for a considerable distance whereby snow of small depth may be discharged laterally 45 by said moldboard, shafts adjacent the top of said moldboard extending outwardly and rearwardly along the same, helical blades forming conveyors carried by said shafts, a chamber in the rear of said moldboard, means for driving said shafts for engaging snow by said conveyors and moving the same into said chamber if said snow is of great depth, a shaft adapted to be connected to a motor on a propelling vehicle for said plow, gears secured to said first mentioned shafts, and 50 gears driven by said last mentioned shaft for driving said first mentioned shafts and conveyors.

8. A snow plow having in combination, a mold- 55 board for discharging snow outwardly and laterally, said moldboard being of considerable height, 60 conveyors at the top of said moldboard for en- 65 gaging snow if it is of great depth, a casing in the rear of said moldboard at the top thereof hav- 70 ing a chamber therein to which snow is moved by said conveyors, said casing having an opening 75 forming a discharge opening from said chamber, means for propelling snow from said chamber through said opening, a deflector movable to op- 80 posite positions for deflecting snow to one side or the other as it moves through said opening and 85 means for driving said last mentioned means in opposite directions respectively in accordance with the position of said deflector.

9. A snow plow having a moldboard extending outwardly and rearwardly from a central ver- 70 tically extending line, said moldboard extending upwardly for a considerable distance whereby snow of small depth may be discharged laterally by 75 said moldboard, a pair of rotary conveyors dis- 80 posed adjacent the top of said moldboard and ex- 85

tending longitudinally of said mold board in opposite directions from adjacent the center thereof for engaging and moving snow if it is of great depth and means for driving said conveyors.

- 5 10. A snow plow having a moldboard extending outwardly and rearwardly from a central vertically extending line, said moldboard extending upwardly for a considerable distance whereby snow of small depth may be discharged laterally by said moldboard, a rotary conveyor disposed adjacent the top of said moldboard and extending along the same substantially parallel to the surface thereof for engaging and moving snow if it is of great depth and means for driving said conveyor.
- 10 15. 11. A snow plow having a moldboard extending outwardly and rearwardly from its central portion, plates extending in a substantially vertical plane at the outer sides of said moldboard and adapted to cut through the snow to form a regular bank at the edge of the swath made by said plow, and means for holding said plates in different positions so that a higher or lower cut is made thereby.
- 15 20. 12. A snow plow having a moldboard with a

surface extending laterally and rearwardly from its central portion along which the snow is moved to the outer side of said moldboard, a cutter member extending in a plane at the outer side of said moldboard inclined slightly to the vertical, and means for varying the position of said cutter so that a cut of greater or less depth is made.

15 20. 13. A snow plow having a mold board extending outwardly and rearwardly from a central vertically extending line, said moldboard extending upwardly for a considerable distance whereby snow of small depth may be discharged laterally by said moldboard and rotary conveyors disposed adjacent the top of said moldboard but below the top edge thereof and extending along said moldboard in opposite directions respectively for engaging and moving snow along said mold board if said snow is of great depth and means for driving said conveyors.

20 25. 14. The structure set forth in claim 13, said moldboard at its top extending about the rear of said conveyors and partially over the top thereof.

ARCHIE O. WILLIAMSON. 25
